UNITED STATES PATENT OFFICE.

CHRISTIAN ERICKSON, OF YORK, NORTH DAKOTA.

VENTILATOR.

1,170,436.

Specification of Letters Patent.

Patented Feb. 1, 1916.

Application filed March 3, 1915. Serial No. 11,780.

To all whom it may concern:

Be it known that I, CHRISTIAN ERICKSON, a citizen of the United States, residing at York, in the county of Benson and State of North Dakota, have invented certain new and useful Improvements in Ventilators, of which the following is a specification, reference being had to the accompanying drawings.

- 10 This invention relates to certain improvements in ventilators and has relation more particularly to a device of this general character especially designed and adapted for use in connection with sleeping cars; and
15 it is an object of the invention to provide a device of this general character having novel and improved means whereby a single berth may be ventilated with convenience and facility.
20 The invention consists in the details of construction and in the combination and arrangement of the several parts of my improved ventilator whereby certain important advantages are attained and the device is
25 rendered simpler, less expensive and otherwise more convenient and advantageous for use, all as will be hereinafter more fully set forth.

The novel feature of the invention will be
30 carefully defined in the appended claim.

In order that my invention may be the better understood, I will now proceed to describe the same with reference to the accompanying drawings, wherein—

35 Figure 1 is a longitudinal sectional view taken through a ventilator constructed in accordance with an embodiment of my invention and in applied position; and Fig. 2 is a sectional view taken substantially on the line 2—2 of Fig. 1.

40 As disclosed in the accompanying drawings, W denotes a portion of a wall of a car adjacent a berth section and through which is disposed the sleeve 1 terminating in its
45 outer extremity with the angular disposed funnel 2. The inner extremity of the tubular member or sleeve 1 is intersected by the cross bars 3 provided at their intersecting portion with the thimble 4 through which is dis-
50 posed the elongated shank 5 carried by the cap member 6, said cap member being interiorly threaded, as at 7, and adapted for detachable engagement with the threaded portion 8 of the inner extremity of the sleeve
55 or tubular member 1. It is to be observed that the shank 5 is of such a length as to

permit the cap or closure member 6 to be adjusted away from the inner extremity of the sleeve or tubular member 1 when required and in order to limit the outward movement of the cover or closure member 6, I have the inner extremity of the shank 5 surrounded by the annular member 9 but held against displacement by the cross pin 10.

Surrounding the inner extremity of the tubular member or sleeve 1 is a barrel 11 having its inner extremity provided with an annular flange 12 suitably secured to the inner face of the wall W and provided with an elongated horizontally disposed slot 14 into which is adapted to project the shank 15 of the headed member 16 threaded through the inner projected portion of the tubular member or sleeve 1, whereby it will be perceived that the requisite axial rotation may be imparted to the tubular member or sleeve 1 to control the position of the funnel 2. The slot 14 is preferably of a length to permit the tubular member or sleeve 1 to be rotated 180 degrees so that the funnel 80 may be disposed directly forwardly of the train or rearwardly thereof, as the requirements of practice may dictate.

Under certain conditions it has been desirable to maintain the funnel in adjustments less than 180 degrees and for this reason I provide the inner projected portion of the tubular member or sleeve 1 with the openings or perforations 17 into which is adapted to be projected the spring member 18 carried by the annular flange 12 and operating in a manner which is believed to be clearly apparent to those skilled in the art to which my invention appertains.

In order that axial rotation may be imparted to the sleeve or tubular member with a minimum of resistance, I find it of advantage to provide said sleeve adjacent the inner and outer faces of the wall W with the cones 19, the innermost cone 19 coacting with the annular flange 12 while the outer cone is adapted to coact with an annular plate 20 secured to the outer face of the wall and surrounding the tubular member or sleeve 1. As is believed to be self-evident, suitable anti-friction members are interposed between the cones 19 and the coacting flange 12 and annular plate 20.

From the foregoing description, it is thought to be obvious that a ventilator constructed in accordance with my invention is of an extremely simple and comparatively

inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

The combination of a ventilating tube having a spider arranged in one end thereof provided with a central sleeve in axial alignment with the tube, a cap member of concavo-convex disk-like form provided at its edge with internal screw threads, said ventilating tube having complementary exter-

nal screw threads, a stem projecting axially from the inner face of the cap and slidably engaged in said sleeve whereby the cap is supported in spaced relation to the end of the ventilating tube when said tube is open,²⁵ and means on the end of said stem for preventing the complete disconnection of the same from said sleeve, said stem sliding freely through the sleeve and also rotating therein whereby the threads on the cap may be engaged with the threaded end of the ventilating tube and said cap turned thereon to close the tube.

In testimony whereof I hereunto affix my signature in the presence of two witnesses.³⁵

CHRISTIAN ERICKSON.
